APPARATUS FOR TREATING STEAM HEATING SYSTEMS

Otto J. Bublitz, Milwaukee, Wis.

Application June 5, 1935, Serial No. 25,005

1 Claim. (Cl. 237—1)

The present invention comprises modifications of that described and illustrated in my pending application, Serial Number 19,390, filed May 2, 1935, patented March 9, 1937, Patent No. 2,073,139, for improvements in an Apparatus for treating steam heating systems.

The invention and its modifications will be more fully described in the accompanying specification and drawing in which:—

10 The drawing shows a side view partly in section and partly in elevation of a compound heating and injecting installation embodying my invention.

In the drawing, the line 41 leads directly into the compartment 42 at a low point thereof for the purpose of discharging steam under pressure therein. Said line 41 is provided with a shut-off valve 42 which may be closed to allow the passage of steam through the horizontal line 44, which is coupled to line 41 by means of T-connection 45 and which has a shut-off valve 46 interposed therein adjacent to line 41. Line 47 communicating with the container 42 at 48 thereof provides means of egress for the steam and compound mixture and is joined to line 44 by means of the T-connection 49. On the low side of said T-connection 49 the line 44 has interposed therein the check valve 50 and leads to the main line 51 by means of the T-connection 52. A line 53 is coupled to the main line 51 by means of the T-connection 54 and communicates directly with the coil 55 in container 42. Various elbows 56 and unions 57 are interposed in the lines where they are necessary.

35 In use, this apparatus is capable of two modes

of operation. If the valve 46 be turned off with the valve 43 open, the steam under pressure will enter the container by means of line 41 and will force compound 58 into the main line 51 by means of line 47, T-connection 49 and line 44.

The other method may be employed by closing valve 43 and opening valve 46 whereupon the steam will pass through line 44, the T-connection 49, the check valve 50 and back into line 51 by means of coupling 52 and in so doing will convert the line 47 into a siphoning tube, drawing the mixture by this means into the main line 51. As in the first form of the invention, a heating coil 55 is employed to pre-heat the treating solution and this may be coupled to either the high or low side of the main line.

The device is capable of various modifications in structure and design without departing from the spirit of the invention, all within the scope of the appended claim.

Having thus described my invention, what I claim as new and desire to secure by Letters Patent of the United States, is:—

In combination with a steam heating system having a reducing valve therein, a container for pipe treating compound, a line from the high pressure side of the valve communicating with the container, a heating coil in said container, a line from the low pressure side of said valve coupled with the coil, and a discharge line leading from said container to the heating system whereby the compound will be forced into the pipes thereof.

OTTO J. BUBLITZ. 35
